UNITED STATES PATENT OFFICE

144,464

DESIGN FOR A DECALCOMANIA SHEET OR THE LIKE

William E. Mell, Skokie, Ill., assignor to Mell-Hoffmann Mfg. Co., Chicago, Ill., a partnership

Application October 4, 1945, Serial No. 122,529

Term of patent 7 years

(Cl. D59—2)

To all whom it may concern:

Be it known that I, William E. Mell, a citizen of the United States, residing at Skokie, in the county of Cook and State of Illinois, have invented a new, original, and ornamental Design for a Decalcomania Sheet or the like, of which the following is a specification, reference being had to the accompanying drawing forming part thereof.

In the drawing:

The figure is a plan view of a decalcomania sheet or the like showing my new design.

I claim:

The ornamental design for a decalcomania sheet or the like, substantially as shown.

WILLIAM E. MELL.
